UNITED STATES PATENT OFFICE.

JOHANNES HINSCH, OF SPANDAU, NEAR BERLIN, GERMANY, ASSIGNOR TO SIEMENS SCHUCKERTWERKE G. M. B. H., OF BERLIN, GERMANY, A CORPORATION OF GERMANY.

ROTARY PUMP.

1,287,020.

Specification of Letters Patent. Patented Dec. 10, 1918.

Application filed May 11, 1917. Serial No. 168,032.

To all whom it may concern:

Be it known that I, JOHANNES HINSCH, a subject of the King of Denmark, and resident of Spandau, near Berlin, Germany, have invented certain new and useful Improvements in Rotary Pumps, of which the following is a specification.

My invention relates to rotary pumps and in particular to pumps of the centrifugal type. Its object is to provide a pump of high capacity which allows of being easily converted into a pump of different output and head without requiring any changes to be made on the casing.

According to my invention the shaft centrally located in the casing is arranged to receive a plurality of wheels, which may all be blade-wheels, some of which however may be replaced by solid disks. To this end the wheels and disks are made easily removable from the shaft. In the case where a pump having a large output is required, the blade wheels can be arranged to work in parallel, and in those cases where it is desired to obtain a high head, the blade wheels may be arranged in several stages, the conversion of one type into the other being in all cases an operation of the utmost simplicity.

My invention will be described with reference to the drawings affixed to the specification and forming part thereof, although it is to be understood that many modifications may be made in the devices and combinations herein described without departing from the principle of my invention.

In the drawings I have shown a number of combinations to be obtained with a pump according to my invention, Figures 1 to 5 representing combinations to be effected in a pump of a small type, Figs. 6 to 8 showing a larger type.

Fig. 1 is a vertical longitudinal section of a small type of pump according to my invention. Fig. 2 is a like view of the same pump drawn in a purely diagrammatic manner, same as the rest of the figures. Fig. 3 is a horizontal longitudinal section of the pump shown in Figs. 1 and 2. Figs. 4 and 5 are vertical longitudinal sections of the same type of pump showing the arrangement of wheels after having been converted into pumps of a different capacity. Figs.

6, 7 and 8 are vertical longitudinal sections of a compound pump with its blade wheels arranged in different ways, so as to represent three pumps of different capacity and head respectively.

Referring to Figs. 1, 2, and 3 the casing substantially consists of the pump cylinder proper 1, easily removable covers 2, 2 closing the cylinder at both ends and a longitudinal passage 3 arranged above the cylinder and connecting its ends. 4 is the central shaft running in bearings 5 provided in the covers. 6 and 7 are blade wheels and 8 is a solid flanged disk, all being removably arranged on the shaft. 9 is the inlet and 10 the discharge branch disposed on opposite sides of the casing and on different sides of the center, the solid disk 8 serving as a partition between the two. Both blade wheels are acting in the same direction (from the right to the left). The water or other medium to be conveyed on being drawn in through the inlet 9 by the action of blade wheel 6, after having passed through said wheel, is forced into the longitudinal passage 3 and is drawn from it by blade wheel 7 serving to deliver it through the discharge opening 10.

The pump here described is a two-stage pump whose head is double the head of a pump provided with a single blade wheel, while the water volume delivered is equal to that delivered by a single wheel pump.

The pump here described may easily be converted into a single-stage pump, as shown in Fig. 4, delivering an equal water volume by simply removing the blade wheel 7. The water drawn in through inlet 9 by the action of blade wheel 6 is pressed through the longitudinal passage 3 into the discharge branch 10.

By replacing the solid disk in a pump of this latter type by a second blade-wheel acting in an opposite sense to blade wheel 6 a single-stage pump of increased head is obtained. As shown in Fig. 5 two blade wheels 6 and 11 are arranged on the shaft on both sides of the inlet 9, blade wheel 6 acting from the right to the left and blade wheel 11 from the left to the right. The water is drawn in through the inlet 9 by the action of both wheels, and while wheel 6 presses the water passing through it into the

longitudinal passage 3, blade wheel 11 causes the water passing through it to leave the casing directly through the outlet 10. By this arrangement the output obtained is

5 double that of the pumps described before.

The pumps shown in Figs. 6 to 8 may be said to be combinations of two pumps as shown in Figs. 1 to 5 with the exception of

10 the inlet and discharge branches which in this type of pump are arranged diametrically opposite each other in the middle of the casing.

In the modification shown in Fig. 6 the two halves of the pump are arranged to act

15 in the same manner, blade wheels 6 drawing the water in through the inlet 9 and pressing it into a longitudinal passage 12 arranged below the pump cylinder, while blade wheels 11 draw the water from these passages and

20 press it into the discharge branch 10, the full disks 8 serving as partitions between the two suction chambers on each side. This pump is a two-stage pump having an output double that of the pumps shown in Figs. 3

25 and 4.

The modification shown in Fig. 7 differs from the one just described in that the left hand disk 8 has been replaced by the adjacent blade wheel 11, the corresponding blade 30 wheel 11 on the other side having been removed entirely. In this way a single-stage pump is obtained having a capacity three times as high as that of the pumps shown in Figs. 3 and 4.

35 The pump shown in Fig. 8 has a still higher capacity. It may be said to be a combination of two pumps of the type shown in Fig. 5 inasmuch as two blade wheels acting in different directions are arranged near each end of the inlet passage, 40 no solid disk being provided. This pump is a single-stage pump having a capacity four times as high as that of the pumps shown in Figs. 3 and 4.

45 It is clear that the drawings show merely a few of the different arrangements and combinations to be made in order to obtain pumps of different head and capacity. Thus by placing in a casing according to Figs. 50 6 to 8 three solid disks and only a single blade wheel, a single-stage pump having a capacity equal to that shown in Figs. 3 and 4 would be obtained. By increasing

the number of blade wheels the head and capacity may be increased also at will.

It is an easy matter in this type of pump to arrange the blade wheels in such a manner that the shaft is balanced in all cases against axial pressure. To this end the blade wheels and solid disks are arranged 60 on the shaft in such a way that the solid disks serve as balancing disks for the blade wheels.

I further prefer arranging the blade wheels in such a manner that the stuffing 65 boxes of the pump are surrounded by pressure water in order to avoid their being affected by the diminished pressure on the suction side.

The end covers 2, 2 of the casing being 70 easily removable and the boring of the casing being cylindrical throughout, the shaft and wheels can easily be removed from the casing whenever it is desired to replace one or a plurality of wheels by solid disks or 75 vice versa.

I wish it to be understood that the constructional features shown in the figures and quite especially in Fig. 1 of the drawing are of no avail as far as my invention 80 is concerned, which is absolutely independent of any special mode of construction beyond what has been embodied in the claims.

I claim:—

1. A rotary pump comprising a cylinder, 85 an inlet and an outlet on said cylinder, a shaft centrally located in said cylinder, at least one blade wheel and at least one solid disk removably fastened to said shaft, said disk being arranged to bar the direct passage between said blade wheel and said outlet, and a longitudinal passage extending between the pressure face of said blade wheel and said outlet.

2. A rotary pump comprising a cylinder, 90 an inlet and an outlet on said cylinder, a shaft centrally located in said cylinder, at least one blade wheel and at least one partition between said blade wheel and said outlet, said partition being removably fastened to and adapted to partake in the rotation of the shaft, and a longitudinal passage 10 extending between the pressure face of said blade wheel and said outlet.

JOHANNES HINSCH.
